CLAIM

The ornamental design for display rack, as shown and described.

DESCRIPTION

FIG. 1 is a front right perspective view of a display rack showing my new design;

FIG. 2 is a front elevation thereof;

FIG. 3 is a right side elevation, the left side elevation being the mirror image thereof;

FIG. 4 is a top plan thereof;

FIG. 5 is a bottom plan thereof;

FIG. 6 is a rear elevation thereof; and,

FIG. 7 is an elevational view on line 7—7 of FIG. 1 in the direction of the arrows, on enlarged scale.
